PLAQUE

Robert S. Feeley, Carmel, N. Y.

Application November 6, 1956, Serial No. 43,680

Term of patent 14 years

(Cl. D29—23)

FIG. 1.

FIG. 2.

Figure 1 is a top plan view of the plaque, showing my new design, of which the representation of the cross in the center portion is formed by a depression of that area below the surface of the remaining portion of the plaque, as illustrated by Fig. 2 of the drawing, the representation of the spray of wheat being on the depressed area, all as shown.

Figure 2 is a cross-sectional view along the line 2—2 of Figure 1.

I claim:

The ornamental design for a plaque, substantially as shown and described.
